UNITED STATES PATENT OFFICE.

HAROLD H. WILL, OF SYRACUSE, NEW YORK, ASSIGNOR TO THE WILL & BAUMER CO., OF SYRACUSE, NEW YORK, A CORPORATION OF NEW YORK.

CANDLE-LAMP.

1,292,195.

Specification of Letters Patent.

Patented Jan. 21, 1919.

Application filed September 14, 1915. Serial No. 50,705.

To all whom it may concern:

Be it known that I, HAROLD H. WILL, a citizen of the United States, and a resident of Syracuse, in the county of Onondaga and State of New York, have invented a certain new and useful Candle-Lamp, of which the following is a specification.

This invention has for its object a candle lamp which is particularly simple and light in construction, and highly efficient, strong and durable in use, and it consists in the combinations and constructions hereinafter set forth and claimed.

In describing this invention, reference is had to the accompanying drawings, in which like characters designate corresponding parts in all the views.

Figure 1 is a transverse sectional view, partly in elevation, of a preferable form of my candle lamp.

Fig. 2 is a plan view of the base thereof.

This candle lamp comprises, a base, including an upright wall or cup which incloses a candle receiving space, a candle holder held by the base within the cup, and a chimney supported by said cup.

1 designates the base including a body which is here illustrated as a tray, and an upright wall 2 inclosing the candle receiving space, said wall being disposed centrally of the tray.

3 is the candle holder held within the wall 2, and here shown as in the form of a cup in which the candle 4 is located, the cup being preferably made of transparent glass, and the candle preferably fitting, and being located entirely within the cup.

5 is the chimney which telescopes in the upper portion of the wall 2 and rests at 40 its lower edge against inwardly projecting shoulders 6 provided on the inner side of the upright wall 2 below the upper edge thereof. Preferably the shoulders 6 are formed by indenting the wall 2 at intervals from its 45 outer side.

7 are perforations in the annular wall 2 which extend below the shoulders 6 in order to permit the air to be drawn into the chimney 5 below the chimney to support combustion. The perforations 7 are here 50 shown as ornamental in character.

The tray of the base has a central depression 8 and a groove 9 in the bottom of the depression adjacent the side wall of the depression; the groove 9 providing an ex-

ternal bead 10 on the lower side of the tray of the base upon which bead the base rests. Instead of one continuous groove, and one bead being formed, a number of short grooves and beads may be provided. The 60 base 1 is also provided with a suitable handle 11.

The upright wall 2 fits within the side wall of the depression 8 and said wall 2 is formed with an inturned flange 12 at its 65 lower edge which overlies and closes the groove 9 and also laps upon the bottom of the depression 8, such flange 12 having its inner margin 13 upturned forming an internal upright wall concentric with the wall 70 2 but of less height than the same. The wall 2 and the margin 13 constitute inner and outer concentric walls, and are usually annular in form.

The candle holder rests upon the bottom 75 of the depression 8 and fits the inner annular wall 13, the annular wall 13 holding the candle holder 3 in position.

The chimney or globe 5 may be of suitable form, size and construction, but is here 80 shown as cylindrical in general form with its top contracted as at 14. The contracted top co-operates with the air inlets 7 to keep the candle burning without flickering.

What I claim is:

1. A candle lamp comprising a base formed with inner and outer upright walls spaced apart and projecting upwardly above the face of the base so that the inner wall is located within the outer wall with an annular space between them, a candle holder having its lower portion seated within the inner wall, and a chimney carried by the outer wall above the inner wall, the candle holder projecting above the inner wall, substantially as and for the purpose described. 90

2. A candle lamp comprising a base including a tray, and a wall having a major part rising from the tray centrally thereof and inclosing a candle receiving space, the 100 wall having an inturned flange at its lower edge, the flange having its inner margin bent upwardly forming an annular wall concentric with said major part, a candle holder having its base fitting the inner annular 105 wall, and a chimney supported by said major part, substantially as and for the purpose described. 110

3. A candle lamp comprising a base including a body formed with a central de- 110

pression, and with an internal groove around the outer margin of the bottom of the depression, the groove providing an external bead on which the base rests, the base 5 also including an upright wall fitting the side wall of the depression and having an in-turned flange at its lower edge covering said groove, a candle located within the upright wall, and a chimney supported by said wall, 10 substantially as and for the purpose described.

4. A candle lamp comprising a base including a body formed with a central depression, and with an internal groove around 15 the margin of the bottom of the depression, the groove providing an external bead on which the base rests, the base including an upright wall fitting the side wall of the depression and having an in-turned flange at its 20 lower edge covering said groove and lapping the bottom of the depression, said flange having its inner margin extending upwardly and arranged concentric with the major part of said upright wall, a candle 25 holder having its lower portion fitting with-

in said margin, and a chimney supported by said major part of the annular wall, substantially as and for the purpose specified.

5. A candle lamp comprising a base including a tray formed with a central depression, and an upright wall fitting the central depression and inclosing a candle receiving space, the wall being formed with an in-turned flange lapping the bottom of the 30 depression, the flange having its inner margin turned upwardly into a position concentric with the major part of said wall, said major part being formed with a shoulder below its upper edge, a candle holder 35 having its lower portion fitting said inner margin, and a chimney extending into the upright wall and resting on the shoulder, substantially as and for the purpose set forth. 40

In testimony whereof, I have hereunto signed my name, at Syracuse, in the county of Onondaga, and State of New York, this 13th day of Sept., 1915.

HAROLD H. WILL.
